UNITED STATES PATENT OFFICE.

HARRY M. TOWNSEND, OF MINATARE, NEBRASKA.

ENGINE-STARTER.

1,307,941.

Specification of Letters Patent. Patented June 24, 1919.

Application filed May 4, 1918. Serial No. 232,594.

To all whom it may concern:

Be it known that I, HARRY M. TOWNSEND, a citizen of the United States, residing at Minatare, in the county of Scotts Bluff and State of Nebraska, have invented new and useful Improvements in Engine-Starters, of which the following is a specification.

This invention relates to engine starters and particularly mechanical engine starters in which an energy storing spring is utilized in connection with a novel arrangement of gearing whereby the power stored in the spring may be transmitted to the engine shaft for rotating the latter and effecting a starting of the engine. The improved starter may be repeatedly operated where the engine is difficult to start, as for example, in very cold weather.

With the above and other objects in view, 20 the invention consists in the novel construction, combination and arrangement of parts, as herein described, illustrated and claimed.

In the accompanying drawings,

Figure 1 is a diagrammatic plan view of 25 the forward portion of a motor vehicle, illustrating the applied relation of the starting mechanism thereto.

Fig. 2 is an enlarged plan view of the 30 starter.

Fig. 3 is a vertical cross section through 35 the same, taken adjacent to the gears on the starting shaft and the countershaft on the line 3—3 of Fig. 1.

Fig. 4 is a fragmentary vertical transverse 40 section illustrating the operation of the pawl on the line 4—4 of Fig. 2.

Referring to the drawings, 1 designates the engine shaft of an internal combustion engine as employed in motor vehicle practice.

In carrying out the present invention, I place a ratchet wheel 2 on the shaft 1 and key or otherwise secure the same thereto so that said ratchet wheel rotates with the shaft 45 1 while the engine is in operation.

3 designates the starting shaft, which is arranged in front of the engine shaft and in longitudinal alignment therewith. Fast on the rear end of the shaft 3 is a gear 4 which 50 meshes with another gear 5 on a counter-shaft 6 journaled in bearings 7 projecting from the frame plate or base 8 of the starter. The shaft 6 has incorporated therein one or 55 more tumbling joints 9 and the rear section of said shaft extends rearwardly through the dash 10 of the vehicle, in rear of which it is

provided with an operating crank 11 by means of which the operator, while sitting in his seat in the machine, may rotate the shaft 6 and by means of the gears 4 and 5 60 impart rotary motion to the shaft 3 for a purpose which will appear.

An energy storing spring 12 encircles the shaft 3 and has its inner end fastened to said shaft 3, while its outer extremity is secured to a fixed stud 13 having a fixed relation to the base or frame plate 8. The spring 12 is arranged just in front of the gear 4. Connected to and carried by the gear 4 is a pawl or dog 14 which is adapted to engage the ratchet wheel 2. 15 designates the operating crank for primarily winding the spring. At a suitable point on the base or frame plate is a stop shoulder 16 while the pawl 14 has a projecting shoulder or stop 17 which is adapted to rest against the stop 16 and hold the engaging point or free end of the pawl out of engagement with the ratchet wheel after the engine has started and the starting mechanism has been operated to 75 perform its function. In winding the energy storing spring by means of the shaft 6, the pawl 14 clicks over the teeth of the ratchet wheel but engages said wheel as the spring unwinds so that when the spring 12 80 is released, the pawl engages the teeth of the ratchet wheel 2 thus causing the energy of the spring to be transmitted to said ratchet wheel and consequently to the engine shaft, the same resulting in turning over the engine shaft several times or until the engine takes over its own operation of cycle.

The shaft 6 is slidably mounted in its bearings so that when the operator is desirous to use the starter he pulls rearwardly on the shaft 6 sliding the gear 5 out of engagement with the gear 4 and thereby releasing the gear 4 and enabling the energy of the spring to be imparted to the ratchet wheel 2 and the engine shaft. In order to rewind 95 the energy storing spring the operator slides the gear 5 again into mesh with the gear 4 and completes the winding of the spring by proper manipulation of the crank 11.

It will, of course, be understood that the 105 energy storing spring may be made of any desired size and power, the same varying in accordance with the power of the engine in connection with which the starter is used. It will also be understood, of course, that in 110 some cases a plurality of energy storing springs may be employed where a consider-

able amount of power is required to turn the engine shaft.

After the operator starts the engine, the energy storing spring is wound and is thereafter held under tension until the pawl 14 is released from the stop 16. The said release of the pawl 14 is accomplished by slightly revolving the shaft 3 by means of the shaft 6 and crank 11, and the pawl then moves into engagement with the ratchet wheel 2 with the result that the energy-storing spring is utilized to turn the shaft 1 and start the engine. The spring 12 is primarily wound by means of the crank 15. To start the engine the shaft 6 is partly rotated by the crank 11 until the pawl 14 engages the ratchet wheel 2. The gear 5 is then slid out of mesh with the gear 4 by moving the shaft 6 endwise, which frees the gear 4 causing the pawl 14 to rotate the wheel 2 and turn the engine shaft. The spring is rewound by turning the crank 11 after sliding the gear 5 into mesh with the gear 4.

I claim:—

- 25 1. The combination with an engine shaft, of a ratchet wheel fast thereon, a starting shaft located in longitudinal alinement with said engine shaft, an energy storing spring having one end secured to a fixed point and the other extremity secured to said starting shaft, a gear on said starting shaft, a pawl carried by said gear and shiftable into and out of engagement with said ratchet wheel, a countershaft substantially parallel to the

engine shaft and slidable longitudinally, a gear fast on said countershaft and adapted to mesh with the gear on the starting shaft, said gear on the countershaft being slidable therewith into and out of mesh with the gear on the starting shaft, and means for detachably holding said pawl out of engagement with the ratchet wheel to prevent the spring from unwinding, the pawl being released from said means by movement of the gear by which the pawl is carried. 35

2. The combination with an engine shaft, of a ratchet wheel fast thereon, a starting shaft located in longitudinal alinement with said engine shaft, an energy storing spring having one end secured to a fixed point and 50 the other extremity secured to said starting shaft, a gear on said starting shaft, a pawl carried by said gear and shiftable into and out of engagement with said ratchet wheel, a countershaft substantially parallel to the 55 engine shaft and slidable longitudinally, a gear fast on said countershaft and adapted to mesh with the gear on the starting shaft, said gear on the countershaft being slidable therewith into and out of mesh with the gear on the starting shaft, a stop shoulder on said pawl, and a fixed stop shoulder with which the first named stop shoulder is adapted to engage for holding the pawl out of engagement with the ratchet wheel and preventing said spring from unwinding. 60

In testimony whereof I affix my signature.
HARRY M. TOWNSEND.
